UNITED STATES PATENT OFFICE.

JOHN R. MAGARVEY, WILLIAM DALTON, AND CHARLES L. HEISLER, OF SCHENECTADY,
NEW YORK.

MEANS FOR SUPPLYING COMMINUTED FUEL TO FURNACES.

1,177,045.

Specification of Letters Patent. Patented Mar. 28, 1916.

Application filed June 8, 1914. Serial No. 843,682.

To all whom it may concern:

Be it known that we, JOHN R. MAGARVEY, WILLIAM DALTON, and CHARLES L. HEISLER, all of Schenectady, in the county of Schenectady and State of New York, have jointly invented a certain new and useful Improvement in Means for Supplying Comminuted Fuel to Furnaces, of which improvement the following is a specification.

10 Our invention relates to the storage, pneumatic conveyance, and feeding to one or more furnace chambers, of fuel in a comminuted condition, and its object is to provide means whereby fuel which is comminuted in a centrally located pulverizing apparatus may be conveyed therefrom, and distributed, without waste or escape of dust, to a plurality of feeding hoppers located adjacent to furnaces in different portions of a 15 large manufacturing plant.

15 The improvement claimed is hereinafter fully set forth.

In the accompanying drawings: Figure 1 is a view, partly in elevation and partly in vertical longitudinal central section, of a pulverizing mill designed for the practice of our invention; Fig. 2, a transverse section through the same, on the line *a a* of Fig. 1; Fig. 3, a view in elevation of a battery of 20 boilers to which our invention is applied; Fig. 4, a vertical section on the line *b b* of Fig. 3; and, Fig. 5, a plan or top view.

The fuel which is to be burned in a comminuted condition is delivered from a car, 1, running on a railroad track, 2, to a receiving hopper, 3^a, located adjacent to one end of a mill building, 3, in which there are installed crushing, pulverizing and storing appliances of substantially the following 25 construction. The fuel drops from the receiving hopper into a crusher, 4, which may be of any suitable and preferred known construction, and which, as it does not, in and of itself, form part of our present invention, 30 is herein only diagrammatically indicated. The fuel, after having been broken, by the crusher, into lumps of comparatively small size, is lifted therefrom and carried to the top of the mill building by an elevator, 5, 35 which deposits it in a pair of preliminary storage hoppers, 6, from which it drops, by gravity, into two rotary driers, 7, disposed adjacent to opposite sides of the mill, in which, in order to prevent interruption, 40 there are installed two duplicate sets of dry-

ing and grinding appliances, the description of one of which will apply to both.

A small heating furnace, 8, is located in the mill building, at a level below that of the drier, and is connected therewith by a flue, 60 10. After passing through and returning from the drier, the smoke, and any dust that may have collected from the drier rise upward through the flue, 10^a, and enter the air and fuel cyclone separator, 11, wherein 65 the dust is precipitated, and thence passes, through the conduits, 11^a, to the fuel pulverizers, 12. The waste gases of combustion are discharged through the stack, 10^b, which projects above the top of the mill building. 70 The crushed and dried fuel is discharged from the lower ends of the driers, 7, into the crushed fuel storage hoppers, 13, from which it is carried by screw conveyers, 14, to the fuel pulverizers, 12. The latter may be of any suitable and preferred construction, many of which are known in the art, and are driven by belts, 15, from motors, 16.

An air compressor, 17, adapted to deliver air at a pressure of about 75 pounds per 80 square inch, is connected by pipes, 19, controlled by valves, 20, with the tops of two or more fuel storage and blowing chambers, 18, a plurality of chambers being provided to insure continuous operation, which is attained by making the chambers, 18, of sufficient volume to enable fuel to be ground and stored in one of them, while fuel is being blown out of the other. The chambers, 18, are connected with the pulverizer, 12, by 85 conduits, 21, in which are fitted screw conveyers, 22, which are rotated, through a gear, 21^a, in direction to carry pulverized fuel from the pulverizer to the chambers, 18, and the discharge ends of the conduits, 90 within the chambers, 18, are controlled by outwardly opening check valves, 23, to prevent the escape of air into the pulverizer, when it is admitted to either of the chambers, 18, from the compressor, 17. As shown 95 in Fig. 1, the right hand chamber, 18, is being filled from the pulverizer, the air supply being cut off, and the left hand chamber, 18, is under air pressure and is being discharged, communication with the pulverizer 100 being cut off by the check valve, 23, of said chamber. Continuous operation of the pulverizer is thereby afforded, and it will be obvious that additional pairs of fuel blowing chambers may be provided, if desired. 105 110

Pulverized fuel pneumatic conveying pipes, 24, extend outwardly from the mill, 3, to any desired points in a manufacturing plant, said pipes projecting into the chambers, 18, and terminating, by open lower ends, near the bottoms of said chambers. Sleeves, 25, surround the pipes, 24, within the chambers, and are vertically movable therein by pinions, 25^a, engaging racks 5 the sleeves and manually actuated by hand wheels, 25^b. Annular air passages are formed around the pipes, 24, by the sleeves, 25, and when either sleeve is in its lowest position, as shown in the right hand chamber, 18, in Fig. 1, the flow of pulverized fuel to the open bottom end of the pipe, 24, is cut off, and air admitted from the compressor by opening the valve, 20, controlling the pipe, 19, leading to the chamber, would 10 have free passage into the blowing chamber, through the annular space around the pipe, 24, and thence upwardly into said pipe, thereby enabling the pipe to be cleaned out without disturbing the pulverized fuel in 15 the chamber. By lifting the sleeve, 25, to the position shown in the left hand blowing chamber, 18, and opening the valve, 20, controlling the admission of compressed air to said chamber, pulverized fuel will flow into 20 the open lower end of the pneumatic conveying pipe, 24, thereof, and will be jetted upwardly therein by the air which enters the annular space between said pipe and its surrounding sleeve, 25. The operation will 25 be the same if suction is applied to the outer or delivery end of the pipe, 24, instead of admitting air from the compressor, under which conditions air will flow from the atmosphere into the chamber, past the flap 30 check valve, 26, which is shown open, in dotted lines, in Fig. 1. It will therefore be seen that pulverized fuel may be conveyed through either of the pipes, 24, either by pressure from the air compressor, 17, or by 35 suction or a partial vacuum induced by a fan, 34, which is shown in Figs. 3, 4, and 5, as connected to the delivery end of one of the pipes, 24.

The pneumatic conveying pipes, 24, when 40 extending for a considerable distance from the mill, 3, may, from time to time, become clogged, and for the purpose of relieving them from any accumulation of pulverized fuel, we provide for the admission of air 45 under pressure at different points, and clearing out sections of the pipes, 24, by means of a supplemental clearing pipe, 30, of smaller diameter, which is connected to the compressor, 17, and controlled by a valve, 50^a. Station by-pass valves, 30^b, are fitted in 55 connections disposed at intervals along the pipes, 30, and 24, to provide convenient means for admitting air from the former to the latter. Branch pneumatic conveying 60 pipes, 24^a, may be connected with the pipes, 65

24, when it is desired to provide additional outlets, the branch pipes being governed by gate valves, 24^b, and their discharge outlets by gate valves, 24^c.

The discharge end of one of the pipes, 24, 70 is shown, in Figs. 3, 4, and 5, as connected to a cyclone separating chamber, 31, and the discharge end of another pipe, 24, to the suction fan, 34, before specified. The fan, 34, is also shown as discharging, by the 75 conduit, 33, into the cyclone separating chamber, 31, and is driven by a motor, 36, which is coupled to a larger fan, 37, and also drives a pair of intermeshing gears, 38, secured on the shafts of a pair of screw conveyers, 40, which rotate in opposite directions in, and distribute pulverized fuel through, horizontal cylindrical feed hoppers, 31^a, which project, in opposite directions, from the cyclone separating chamber, 80 31, and communicate with a plurality of feed valves, 41, rotated by a shaft, 41^a, which is actuated by the shaft of one of the gears, 38.

The casings of the feed valves, 41, are connected by fuel feed pipes, 42, with low pressure air blast burner pipes, 43, near the discharge ends of the latter in furnaces, 44, forming part of boiler settings, 45, of any of the well known types. Each set of blast 90 burner pipes is connected with a manifold, 46, to which air is supplied from the fan, 37, through conduits, 47. The suction side of the fan is connected by a conduit, 50, governed by a valve, 50^a, with the top outlet 100 of the cyclone separating chamber, 31. The fan is also provided with a supplemental suction air inlet, 51, controlled by a valve, 51^a. Any desired number of separating 105 chambers, 52, of known construction, may be connected with the fan, 37, by conduits, 52^a, controlled by valves, 52^b, thereby preventing any escape of dust from the separating chambers, and discharging it through the 110 conduits, fan, manifolds, and burner pipes 110 into the furnaces. Any of the separating chambers may be connected by a conduit, 53, with a feed box, 54, connected to a furnace, 44^a, by a burner pipe, 43^a, to which air from any available source may be supplied 115 through a conduit, 43^b.

The detailed construction of the furnaces to which pulverized fuel is supplied by our invention as hereinbefore described, and the burners and other accessories thereof 120 may be of any of the many well known types known in the art, and as they do not form part of our present invention, they are not herein at length set forth.

We claim as our invention and desire to 125 secure by Letters Patent:—

1. In an apparatus for supplying comminuted fuel to furnaces, the combination of a drier, means to supply fuel thereto, a pulverizer to receive the fuel from the drier, 130

a dust collector connected to the drier and also to the pulverizer, a fuel storage and blowing chamber to receive the fuel from the pulverizer, a separator, a conduit connecting said chamber and separator, means to cause a current of air to flow through said conduit, means to convey the fuel from said separator into a furnace inlet, and means to cause a current of air to flow from 10 said separator into said inlet.

2. In an apparatus for supplying comminuted fuel to furnaces, the combination with means for drying and pulverizing fuel, of a chamber in which the pulverized fuel 15 is received, means to force air into said chamber, a fuel discharge pipe from said chamber having its inlet end near the bottom thereof, a sleeve surrounding said pipe within said chamber to form an annular 20 air passage from the upper part of said chamber to the inlet end of said pipe, means for moving said sleeve longitudinally of said pipe so as to prevent the fuel from entering the latter while permitting the air to do so, 25 and means to convey the fuel from said pipe into a furnace.

3. In an apparatus for supplying comminuted fuel to furnaces, the combination with a fuel drier and pulverizer, of a plurality of chambers to receive the fuel therefrom, means to admit air into said chambers and to prevent its escape therefrom into the pulverizer or atmosphere, a fuel discharge pipe leading from each chamber to 30 a furnace, means in each chamber to prevent the fuel from entering said pipe when so desired while permitting the air to do so, and means to cause an outward flow of air through said pipe.

4. In an apparatus for supplying com- 40 minuted fuel to furnaces, the combination with a conduit for the fuel and means to cause a current of air to flow therethrough, of a separator into which said conduit leads, a plurality of furnace inlets, a conveyer to 45 receive the fuel from said separator and distribute it to said inlets, a blower connected to said separator and also to said inlets, secondary separators connected to said conduit and also to said blower, and means to 50 prevent the fuel from entering said conduit while maintaining the air current therein.

5. In an apparatus for supplying com- 55 minuted fuel to furnaces, the combination of a fuel hopper, an inclined rotary drier to receive the fuel from said hopper, a fuel storage and blowing chamber to receive the fuel from said drier, a dust separator connected to said drier and also to said chamber, a fuel discharge pipe leading from the 60 lower part of said chamber, means to cause a current of air to flow outwardly through said pipe, means to prevent the fuel in said chamber from entering said pipe when desired while still permitting the air to flow 65 therethrough, a separator into which said pipe leads, a plurality of furnace inlets, a conveyer to receive the fuel from said separator and distribute it to said inlets, and a blower to withdraw air from said separator 70 and force it into said inlets.

JOHN R. MAGARVEY.
